United States Patent Office

Des. 218,267

Patented Aug. 4, 1970

218,267

SUIT CASE

Paul Belokin, Jr., 1603 Orrington Ave.,
Berwyn, Ill. 60201

Filed Mar. 24, 1969, Ser. No. 16,402

Term of patent 14 years

Int. Cl. D3—01

U.S. Cl. D87—5

FIG. 1

FIG. 2

FIG. 3

FIG. 5

FIG. 4

FIG. 1 is a perspective view showing the appearance of my new design of a suit case:

FIG. 2 is a side view of the suit case with the slide fastening partly open;

FIG. 3 is a top view of the suit case;

FIG. 4 is a bottom view of the suit case; and

FIG. 5 is an end view of the suit case.

The opposite side and end are plain and unornamented.

I claim:

The ornamental design for a suit case, as shown and described.
